UNITED STATES PATENT OFFICE.

THEODORE SCHAFER, OF MAROA, ILLINOIS.

DESIGN FOR A FAUCET-STEM.

SPECIFICATION forming part of Design No. 24,344, dated May 28, 1895.

Application filed November 14, 1894. Serial No. 528,819. Term of patent 14 years.

To all whom it may concern:

Be it known that I, THEODORE SCHAFER, of Maroa, in the county of Macon and State of Illinois, have invented a certain new and use-
ful Design for Faucet-Stems; and I do hereby declare the following to be a full, clear, and exact description of the invention, such as will enable others skilled in the art to which it pertains to make and use it, reference being had to the accompanying drawing, which forms part of this specification.

My invention relates to designs for faucet stems, illustrated in the accompanying drawing, which is a perspective view of the same.

The characteristic features of my design consist of the main or body portion A, hav-

ing its outlet B turned down as usual, and a configuration formed by the longitudinally outwardly extending arm C, and the laterally extending arms D.

Having thus described my design, what I claim, and desire to secure by Letters Patent, is—

The design for a faucet stem substantially as herein shown and described.

In testimony whereof I affix my signature in presence of two witnesses.

THEODORE SCHAFER.
